UNITED STATES PATENT OFFICE.

EUSEBIUS E. HERSHY, OF PHILADELPHIA, PENNSYLVANIA, ASSIGNOR TO VACUUM CLEANER MANUFACTURING COMPANY, OF PHILADELPHIA, PENNSYLVANIA, A CORPORATION OF NEW JERSEY.

DESIGN FOR A VACUUM-CLEANER.

42,753.

Specification for Design.

Patented July 9, 1912.

Application filed April 12, 1912. Serial No. 690,367. Term of patent 14 years.

To all whom it may concern:

Be it known that I, EUSEBIUS E. HERSHY, a citizen of the United States, residing at Philadelphia, in the county of Philadelphia and State of Pennsylvania, have invented a new, original, and ornamental Design for Vacuum-Cleaners, of which the following is a specification, reference being had to the accompanying drawing, forming a part thereof.

Figure 1 is a plan view of a vacuum cleaner showing my new design. Fig. 2 is a front end view thereof.

I claim:—

The ornamental design for a vacuum cleaner as shown.

EUSEBIUS E. HERSHY.
